Primary Examiner — Ryan Harvey(74) *Attorney, Agent, or Firm* — Meister Seelig & Fein PLLC(57) **CLAIM**

The ornamental design for a motion tracking exercise console, as shown and described.

DESCRIPTION

FIG. 1 is a front perspective view of an embodiment of a motion tracking exercise console according to the new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view of a second embodiment of a motion tracking exercise console according to the new design;

FIG. 9 is a front view thereof;

FIG. 10 is a rear view thereof;

FIG. 11 is a left side view thereof;

FIG. 12 is a right side view thereof;

FIG. 13 is a top plan view thereof; and,

FIG. 14 is a bottom plan view thereof.

The broken line showing of portions of the motion tracking exercise console forms no part of the claim.

1 Claim, 14 Drawing Sheets(56)
